UNITED STATES PATENT OFFICE.

WILLIAM L. HIGGINS, OF BUFFALO, NEW YORK.

OIL BURNER FOR FURNACES.

Application filed November 28, 1923. Serial No. 677,550.

To all whom it may concern:

Be it known that I, WILLIAM L. HIGGINS, a citizen of the United States, residing at Buffalo, in the county of Erie and State of New York, have invented certain new and useful Improvements in Oil Burners for Furnaces, of which the following is a specification.

The present invention relates to an oil burner intended for heating plants or furnaces, and is constructed so that it may be installed in old furnaces built for coal or other fuel as well as in newly erected furnaces adapted for oil fuel alone.

10 The main object of the invention is to provide a burner which automatically prepares the fuel mixture in the correct proportions and maintains the mixture in this condition during the entire operation of the furnace. The burner after once started causes the oil to be vaporized and the steam generated by the heat in the combustion chamber, while air is supplied by the furnace draft.

15 Another object of the invention is to furnish a pilot burner for starting the vaporization of the oil and the generation of steam, which pilot burner may be cut off as soon as the main burner is running properly by stopping the supply of gas.

Another object of the invention is to insure the proper circulation of the water while being heated, thus preventing the formation of scales in the steam pipes, which 35 ordinarily is very detrimental in the operation of similar devices, as the scale produced by water containing lime settles on the walls of the coils clogging the same and in a short while putting the burner out of commission.

40 In order to prevent this, a small boiler or head is attached to the steam coil in which the water is constantly agitated so that no settlement can take place of the lime on the walls of the boiler or the steam pipes.

45 Still another object of the invention is to provide a small reservoir adjacent the nozzle of the oil supplying pipe, so that when the heat in the furnace is lowered and no vaporization of the oil takes place, the oil 50 will return to this reservoir which is preferably so connected with a valve system for supplying the oil, that the valves are automatically closed when the level of the oil reaches a certain height in the reservoir.

55 This has the advantage over other similar devices that the interior of the furnace will

never be flooded with oil and the burner is kept clean and in perfect condition at all times. Such a valve system is described in my co-pending application Serial No. 677,549, filed November 28, 1923.

In the accompanying drawings, one embodiment of the invention is illustrated; and—

Figure 1 is a fragmentary vertical section 65 of a furnace with the burner installed;

Figure 2 is a top plan view of the burner with parts broken away;

Figure 3 is a vertical section of the boiler; 70 and

Figure 4 is a fragmentary side elevation thereof.

In the drawings, reference numeral 10 represents the lower part of a furnace, and reference numeral 11, the ash pit thereof, 75 above which the usual grates 12 are to be found. When installing this burner in furnaces originally intended for coal consumption, one or more of the grate bars 12 are removed and the burner inserted through the ash door and between the removed grate bars carried on a proper stand.

The stand consists of a base plate 13 carried on suitable props or legs 14 extending to the bottom of the ash pit. On top of this base plate is secured a horn 15 forming an air duct for the burner. This horn is secured between flanges 16 and 17 on the base plate and over an opening 18 in the plate, so that the atmospheric air is conducted through the upright shank 19 of the horn and carried downwardly by the bent upper end 20 of the horn, so that the air will be discharged through the mouth 21 of the horn directly above the vapor mixer 22. 90

The air is sucked in through this horn to replace the waste gas passing out through the chimney flue of the furnace so that no forced draft is needed. The vapor mixer 22 is built in the shape of an inverted truncated cone with thin side walls, and stands with its narrow neck 23 on the base plate 13, to which it is securely attached as by bolts 24. The wide mouth of the vapor mixer is presented underneath the mouth 21 of the horn 15 and in axial alignment therewith so that the upwardly directed current of vapor from the mixer 22 meets and intermingles with the downwardly directed air current from the horn about midway between the two.

Centrally in the neck 23 of the vapor

mixer is upwardly projecting, a nozzle 25 carried in the upper end of the reservoir 26 which is threaded in the base plate 13 and positioned directly below the same in axial 5 alinement with the vapor mixer 22. Into the bottom of this reservoir 26, opens an oil supply pipe 27 connected with an oil tank which is furnished with suitable valves for regulating the quantity of oil furnished 10 to the reservoir 26. The arrangement is preferably made, as already stated, that the valves are automatically closed, shutting off the oil supply directly the oil reaches a certain predetermined level in the reservoir, 15 thereby preventing an overflow in the furnace.

The boiler or steam generator 28 is placed adjacent the vapor mixer 22 and suitably secured on top of the base plate 20 13 by bolts 29 or the like. The axis of the boiler is preferably horizontal and the boiler is provided with a baffle plate 31, see particularly Figure 3, which is preferably made 25 integral with the head plate 32, closing one end of the boiler. This baffle plate 31 is somewhat narrower than the inner diameter of the boiler and its inner end is placed a short distance from the adjacent end of the boiler. In this manner, passages are 30 provided on three sides of the plate which is placed horizontally in the boiler. A water supply pipe 33 enters the boiler at one end thereof in its bottom, and this water pipe connects with a water tank provided with 35 suitable valves for regulating the amount of water furnished the boiler. Such valve arrangement is disclosed in my above named copending application, Serial No. 677,549. Even in this case, the arrangement is made 40 so that when the water reaches a certain predetermined height in the boiler, the valves are automatically closed, thus stopping the supply and preventing the flooding 45 of the interior of the furnace. The steam pipe 34 is secured in the top of the boiler and provided with a number of coils 35 which are situated between the mouths of the horn 15 and the vapor mixer 22, as best seen in Figures 1 and 2. The axis of 50 the coils is concentric with the axis of the vapor mixer 22 and preferably of greater diameter than the mouth of the same, or approximately of the same interior diameter 55 as the mouth 21 of the horn 15. The lowermost coil has a downwardly extending portion 36 which enters the vapor mixer 22 at the neck thereof, so that the steam meets the current of vaporized oil directly over 60 the nozzle 25, as seen in Figure 1.

On the side of the boiler 28 facing the vapor mixer 22 are situated a series of corrugated heating plates or radiating webs 37. Directly below these radiating webs is situated 65 a small pilot burner 38, to which gas is supplied through the pipe 39 entering

through the bottom of the base plate 13, and a similar pilot burner 42 is furnished to heat the reservoir 26.

In order to prevent air from entering 70 through the ash pit into the combustion chamber of the furnace 10, except through the horn 15, an asbestos or similar fireproof lining 40 is placed around the base plate 13 over the grate bars 12 and reaching over to the side of the furnace 12, as indicated in 75 Figure 1.

When operating the burner, the valves from the supply tanks are properly set to furnish the correct amount of oil and water and the small pilot burner 38 is lighted. This furnishes heat to the radiating webs 37, which is communicated both to the boiler 28 and the vapor mixer 22. After a short while, steam is generated in the boiler and carried into the vapor mixer 22 while at the same time, the oil in the reservoir 26 commences to vaporize. The oil vapor and the steam intermingling in the vapor mixer 22 and then ascend together to meet the descending air from the mouth 21 of the horn 15 and this fuel mixture is then ignited from the flame of the pilot burner 38, whereupon the combustion takes place and the interior of the furnace 10 is heated.

Having thus described the invention, what is claimed as new is:

1. An oil burner for a combustion chamber comprising a base forming the bottom of the combustion chamber, a nozzle in said base connected with an oil supply, an oil vaporizer, means for mixing the fuel vapors including an inverted hollow cone with a thin side wall, a steam pipe opening adjacent said nozzle in said side wall, and a duct adapted to discharge atmospheric air to mingle with the steam and vaporized oil to make a suitable fuel mixture.

2. An oil burner for a combustion chamber comprising a base forming the bottom of the combustion chamber, a nozzle in said base, a reservoir to which the nozzle is attached, said reservoir being connected with an oil supply and constituting a vaporizer, means for mixing the fuel vapors including an inverted hollow cone with a thin side wall, a steam pipe opening adjacent said nozzle in said side wall, and a duct adapted to discharge atmospheric air to mingle with the steam and vaporized oil to make a suitable fuel mixture.

3. An oil burner for a combustion chamber comprising a base forming the bottom of the combustion chamber, a nozzle in said base connected with an oil supply, an oil vaporizer, means for mixing the fuel vapors including a hollow member surrounding said nozzle, a steam pipe opening adjacent said nozzle in said hollow member, and a duct adapted to discharge atmospheric air to mingle with the steam and vaporized oil

- to make a suitable mixture; a steam generator positioned adjacent said member on said base and carrying said steam pipe and being suitably connected with a water supply. 5
4. An oil burner for a combustion chamber comprising a base forming the bottom of the combustion chamber, a nozzle in said base connected with an oil supply, an oil vaporizer, means for mixing the fuel vapors including a hollow member surrounding said nozzle, a steam pipe opening adjacent said nozzle in said hollow member, and a duct adapted to discharge atmospheric air to mingle with the steam and vaporized oil to make a suitable fuel mixture; a steam generator positioned adjacent said cone on said base and carrying said steam pipe and suitably connected with a water supply; said steam generator including a boiler, a horizontal baffle in the boiler, radiator webs on said boiler extending towards said hollow cone, and a pilot burner for said radiator webs. 65 70 75
- 10 15 20 25 30 35 40 45 50 55 60 65 70 75 80 85 90 95 100 105 110 115
15. An oil burner for a combustion chamber comprising a base forming the bottom of the combustion chamber, a nozzle in said base connected with an oil supply, an oil vaporizer adjacent the nozzle, means for mixing the fuel vapors including a hollow member surrounding said nozzle, a steam pipe opening adjacent said nozzle in said hollow member, and a duct adapted to discharge atmospheric air to mingle with the steam and vaporized oil to make a suitable fuel mixture; a steam generator positioned adjacent said member on said base and carrying said steam pipe and suitably connected with a water supply; said steam generator including a boiler, a horizontal baffle in the boiler, radiator webs on said boiler extending towards said hollow cone, a pilot burner for said radiator webs, and a fireproof packing inserted between said base and the walls of the combustion chamber. 95
16. An oil burner for a combustion chamber comprising a base forming the bottom of the combustion chamber, a nozzle in said base connected with an oil supply, an oil vaporizer adjacent the nozzle, means for mixing the fuel vapors including an inverted hollow cone with a thin side wall, a steam pipe opening adjacent said nozzle in said side wall, and a duct adapted to discharge atmospheric air to mingle with the steam and vaporized oil to make a suitable fuel mixture; a steam generator positioned adjacent said cone on said base and carrying said steam pipe and suitably connected with a water supply; said steam generator including a boiler, a horizontal baffle in the boiler, radiator webs on said boiler extending towards said hollow cone, a pilot burner for said radiator webs, and a fireproof packing inserted between said base and the walls of the combustion chamber. 100
17. An oil burner for a combustion chamber comprising a base forming the bottom of the combustion chamber, a nozzle in said base, a reservoir connected with an oil supply, and adapted to vaporize the oil passing through the nozzle, means for mixing the fuel vapors including a hollow member surrounding said nozzle, a steam pipe opening adjacent said nozzle in said hollow member, and a duct adapted to discharge atmospheric air to mingle with the steam and vaporized oil to make a suitable fuel mixture; a steam generator positioned adjacent said member on said base and carrying said steam pipe and suitably connected with a water supply; said steam pipe having coils arranged concentrically around the axis of said hollow member and said duct including a horn placed over an opening provided in said base and terminating with a mouth opening over said coils. 110 115
18. An oil burner for a combustion chamber comprising a base forming the bottom of the combustion chamber, a nozzle in said

In testimony whereof I affix my signature
WILLIAM L. HIGGINS.
